UNITED STATES PATENT OFFICE.

GEORGE A. CUTLER, OF ST. LOUIS, MISSOURI.

COMPOUND FOR PRESERVING FRUIT, &c.

SPECIFICATION forming part of Letters Patent No. 228,804, dated June 15, 1880.

Application filed October 18, 1877.

To all whom it may concern:

Be it known that I, GEORGE A. CUTLER, of the city of St. Louis, in the State of Missouri, have invented a certain new and useful 5 Compound for the Preservation of Fruits, Meats, &c., of which the following is a specification.

My improvement relates to the chemical compound used in the production of the gases employed in treating the articles to be preserved.

This compound consists of sulphur, four parts; borate of soda, one part; nitrate of potash, one. These are mixed together in a metallic dish or pan, and are ignited by placing over a fire, and when ignited are placed 15 on a shelf within a case near the top. The borate of soda is a powerful antiseptic, and in my compound it plays an important part from this cause. The nitrate of potash supplies oxygen to the burning compound, and thus prolongs the combustion and the consequent elimination of sulphurous and boracic-acid gas.

In carrying out my improvements I prefer 25 to use a case or receptacle which shall be water and air tight, and provided with drawers, shelves, or other conveniences, on which the articles may be placed. The chemicals are laid upon a tray or other convenience in such 30 case and burned, so that the fumes or gas from such burning chemicals may circulate around the articles to be preserved. Said case, it is also preferred, shall have, at or near the bottom, a tank for the reception of water, which

shall be impregnated with the chemicals or 35 their fumes, and in which water articles may be immersed or soaked for preservation. This liquid may be sufficiently impregnated by burning two trays of the chemicals, allowing one hour for the combustion of each.

In the preservation of eggs each egg is placed 40 in a separate aperture of an open-bottomed drawer, and the eggs are subjected to the process for one hour, when they may be taken out and packed away for keeping.

I do not here make any claim to a case such 45 as above described, as I purpose making the same the subject of a separate application for patent.

Large articles, such as meats, &c., should 50 be subjected to the action of the gas for a period of from ten to fourteen hours.

Larger fruits or vegetables are sliced and spread thinly in drawers. They are subjected 55 to the process for about thirty minutes, and then taken out and put into vessels, and soon form a sufficiency of juice, and will keep for any length of time.

I claim as my invention—

The combustible antiseptic compound herein 60 described, composed of sulphur, borate of soda, and nitrate of potash, combined in about the proportions named.

GEORGE A. CUTLER.

In presence of—

SAML. KNIGHT,
ROBERT BURNS.
